UNITED STATES PATENT OFFICE

169,006

GAME BOARD

Marina A. Lee, Norman, Okla.

Application March 31, 1952, Serial No. 19,119

Term of patent 3½ years

(Cl. D34—5)

To all whom it may concern:

Be it known that I, Marina A. Lee, a citizen of the United States, residing at Norman, State of Oklahoma, have invented a new, original, and ornamental Design for a Game Board, of which the following is a specification, reference being had to the accompanying drawing, forming a part hereof.

I claim:

The ornamental design for a game board, as shown.

MARINA A. LEE.
